(57) **CLAIM**

The ornamental design for a coating applicator, as shown
and described.

DESCRIPTION

FIG. 1 perspective view of a coating applicator showing our
new design in an environment of use;

FIG. 2 side view thereof;

FIG. 3 top plan view thereof;

FIG. 4 bottom plan view thereof;

FIG. 5 another perspective view thereof, with the environment
removed;

FIG. 6 another side view thereof, with the environment
removed; and,

FIG. 7 another top plan view thereof, with the environment
removed.

The broken lines showing a cap with applicator tip in FIGS.
1–3 illustrates environmental structure that forms no part of
the claimed design.
